UNITED STATES PATENT OFFICE.

JAMES S. STEWART, OF NEW YORK, N. Y., ASSIGNOR TO ANNIE STEWART, OF NEW YORK, N. Y.

LAMP-RECEPTACLE.

No. 873,104.

Specification of Letters Patent.

Patented Dec. 10, 1907.

Application filed August 17, 1906. Serial No. 330,962.

To all whom it may concern:

Be it known that I, JAMES S. STEWART, a citizen of the United States, residing at the city of New York, in the county of New York and State of New York, have invented certain new and useful Improvements in Lamp-Receptacles, of which the following is a full, clear, and exact description.

My invention relates to lamp receptacles, particularly for the purpose of molding wiring, and relates to a number of features of construction by which the receptacle is simplified and rendered more convenient to manufacture and use.

15 One of the objects of the invention is to provide a simple means for properly locating the receptacle upon the molding while it is being assembled. This is an important practical advantage, since it avoids the 20 necessity of any measurements or special care when the receptacles are being screwed into place.

Another object of the invention is to so form the porcelain base that it will receive 25 any strain put upon the circuit wires, thereby relieving the terminal clips to which it would otherwise be applied.

Still further objects are to enable the threaded shell or sleeve to be fastened to the 30 porcelain base by a single screw and to provide for holding the usual mica disk against accidental displacement. I also aim to make the passages in the porcelain base which receive the circuit wires, smooth and 35 continuous on their sides or walls, so that the circuit wires may be easily drawn into tight or any desired relation without any interference by sharp edges on metallic parts in the receptacle.

40 With these objects in view the invention consists in the features of construction hereinafter described and claimed.

In the drawings: Figure 1 is a top plan view of a receptacle embodying the principles of my invention in place upon a molding; Fig. 2 is a view of the same with the housing removed; Fig. 3 is a section on the line 3—3 of Fig. 2. Fig. 4 is a longitudinal-sectional view showing the insulating base 50 partly in side elevation; Fig. 5 is a detail view showing the mica disk which I employ; Fig. 6 is a similar view illustrating the metallic clip which holds the threaded shell or sleeve in place, and Fig. 7 is a perspective 55 view of the insulating base.

The requirements for lamp receptacles,

rosettes, and similar electrical appliances are based largely on insurance regulations which prescribe that the metallic parts of opposite polarity be separated by porcelain or mica 60 and that similar insulation separate the electrical connections from woodwork. The ordinary circuit wires are carried in molding and it is desirable to have a receptacle which fits upon the ordinary molding and which 65 may be quickly fastened into its permanent relation thereon. In carrying out my invention I attain these purposes and also certain features of practical construction which render the porcelain and metallic parts more 70 easy to manufacture and assemble.

Referring to the drawings in which like parts are designated by the same reference sign, 1 indicates a lamp receptacle upon the molding 2 which has the usual groove 3 in 75 which are laid circuit wires 4 of any suitable or desired character.

5 indicates a cover which may be secured to the molding after the wires are in place.

The receptacle comprises a base portion 6 80 and a housing 7 which fits over the base so as to protect the same and give the receptacle a more ornamental appearance. The features of the housing form more particularly the subject of other applications filed by me, 85 the present invention relating more particularly to the base 6 and its connected parts. Referring more particularly to Figs. 3, 4 and 7, it will be seen that the base 6 has a flat lower surface 8 from which, however, depend 90 integral tongues 9 which are formed and positioned to enter the grooves 3 above mentioned. In this way the base is accurately positioned on the molding without any special care on the part of the workman. 95

The side faces of the base 6 have passages 10 to receive the circuit wires, and the form of the base is such as to present one or more corners 11 which bite against the circuit wires when any longitudinal force is imposed 100 thereon. This is an important feature of the invention because it avoids any undue strain on the terminal connections when the wires are being stretched or pulled into proper relation. The walls 12 of the passages against 105 which the circuit wires bear, are recessed at 13 to receive the terminal clips which form the terminal connections. By having the terminal connections inset in the walls of these passages a perfectly smooth continuous surface is presented to the circuit wires, 110 as clearly shown in Fig. 4. The upper sur-

face 14 of the insulating base 6 has a central protuberance 15 thereon which is conveniently made square for a purpose hereinafter stated.

5 16 indicates a depressed portion of the protuberance 15 which is adapted to receive a small metallic plate 17 which forms the central stud terminal of the lamp.

The threaded shell is indicated at 18, it being obvious that a T-H shell or sleeve could be used in lieu thereof if desired. The lower edge of the shell 18 is flanged inward as shown at 19, and apertured at 20 to fit over the protuberance 15.

15 21 indicates a metallic clip which is also apertured at 22 to fit over the protuberance 15. The protuberance 15 co-operates in a special way with the clip 21 so as to hold the same and the threaded shell securely in place 20 by the use of only a single clamping screw. For this purpose the protuberance is notched on one of its side faces, as shown at 23, and the aperture 22 of the clip 21 is slightly to one side of the central position so that the 25 clip may be slipped over the protuberance and then moved laterally into central position, in which relation it will be engaged in the notch 23 of the protuberance.

24 indicates a clamping screw which is 30 passed upward through the base to hold the clip 22 on the side which is not secured by the notch 23. In this way the clip and the threaded shell are securely fastened to the insulating base. The clip 21 has an extension 35 25 which passes downward through a hole 26 in the base and into one of the passages 10 above described. The lower end of this extension is deflected laterally at 27, said deflected portion falling into the recess 13 of the 40 passage so that the upper surface of the metal and the wall of the passage lie in a continuous unbroken curved surface. In the opposite passage there is contained a clip 28 having a laterally deflected portion 29 similar to the part 27 of the clip 25, and received in the corresponding recess 13 of the other passage 10. The upper end of the clip 28 is received in a cavity 30 in the base and is securely fastened therein by a screw 31 which is passed 50 downward through the plate 17 above mentioned. This screw performs the triple function of holding the plate 17 and the clip 28 in place and establishing an electrical connection between them.

55 32 indicates terminal screws which are received in the clips 25 and 28 so as to establish connection with the circuit wires. The base is recessed at 33 so as to accommodate these screws. The base is also provided 60 with holes 34 through which screws may be passed to secure the base in its position on a molding. The housing 7 may then be placed over the base, resting on ledges 35 thereon, and an insulating bushing 36 screwed upon 65 the shell so as to clamp the housing in place.

From the foregoing it will be seen that when the circuit wires are properly connected beneath the terminal screws 32, the plate 17 and the shell 18, which are in direct electrical connection with the two clips, will be charged to the circuit potential difference. The metallic parts of opposite polarity are, however, separated by a wall or partition of porcelain at every point so that there is no danger of an arc or short-circuit and the insurance regulations are fully complied with.

As an additional precaution against short-circuit I insert in some cases a mica disk 37 which has a central hole 38 corresponding in form to the shape of the protuberances 15 80 but slightly smaller. The mica disk is slit at 39 in radial directions from said aperture 38 so that when the mica is forced over the protuberance, the inside edges will be pressed upward, as clearly shown in Fig. 4. 85 As mica is a resilient material, these edges act to frictionally bite the side faces of the protuberance, so that the mica disk will not thereafter be displaced without special tools or manipulation.

Having described my invention, I claim:

1. In an electrical appliance adapted to be positioned on a molding having longitudinal grooves, an insulating base having a flat lower surface with an integral elongated 95 tongue thereon and projecting from said lower surface of the base intermediate the side edges thereof, said tongue being adapted to enter one of the grooves of said molding whereby the base is properly positioned on the molding when said tongue enters such groove thereof.

2. In an electrical appliance adapted to be positioned on a molding having longitudinal grooves, an insulating base having a flat 105 lower surface with a plurality of parallel elongated tongues projecting from said lower surface of the base intermediate the side edges thereof, said tongues being adapted to enter the grooves of said molding, whereby the base is properly positioned on the molding when said tongues enter the grooves thereof.

3. In an electrical appliance adapted to be positioned on a molding having circuit wires, 115 an insulating base having a flat lower face, and having passages to receive the circuit wires, said passages leading upward from said flat lower face so as to produce edges or corners 11, and which are adapted to bear 120 against the said circuit wires.

4. In an electrical appliance of the class described, an insulating base having a protuberance, one side face of which is notched, a shell or sleeve apertured to fit over said protuberance, a clip having a hole adapted to fit over said protuberance and laterally displaced to enter said notch, and means for additionally holding said clip against the shell, whereby the shell is secured in place.

5. In an electrical appliance of the class described, an insulating base, a shell, said base having a protuberance projecting into the shell, and a mica disk apertured to closely fit said protuberance and slotted so as to frictionally engage the same against withdrawal.

In witness whereof, I subscribe my signature, in the presence of two witnesses.

JAMES S. STEWART.
